UNITED STATES PATENT OFFICE.

LOUIS N. BEAUCHEMIN, OF TACOMA, WASHINGTON.

DESIGN FOR A WEAR-PLATE FOR BOOTS, &c.

SPECIFICATION forming part of Design No. 19,891, dated June 10, 1890.

Application filed May 14, 1890. Serial No. 351,806. Term of patent 14 years. Patented in Canada June 18, 1889, No. 31,621.

To all whom it may concern:

Be it known that I, LOUIS N. BEAUCHEMIN, of Tacoma, in the county of Pierce and State of Washington, have invented and produced 5 a new and original Design for a Wear-Plate for Boots or Shoes, of which the following is a specification, reference being had to the accompanying drawings, forming a part thereof.

This invention has reference to a two-part 10 wear-plate for boots or shoes—that is to say, a sole part and a heel part; and it consists in a novel configuration of the same, substantially as hereinafter described.

Figure 1 represents an inverted plan of a 15 two-part wear-plate showing my new and original design, and Fig. 2 a side view of the same.

A is the sole part or portion of the wear-plate, and B the heel part or portion thereof. 20 The sole part A is of curvilinear form in direction of its length viewed sidewise, the convexity of such shape being underneath. Its marginal configuration, as viewed from beneath, has the form of the main and forward 25 portion of a boot or shoe sole, and it is faci-

ally ornamented by two irregularly-shaped openings C D, the one C of which is approximately of half-moon shape, while the other D is of irregular trapezoidal form with rounded corners. Between and around and about 30 these openings C D the underside of the face of the sole part A is ornamented by pointed or spike-shaped protuberances b. The heel part or portion B of the wear-plate is of straight configuration viewed edgewise and 35 of D shape viewed facially, being ornamented by an opening E, of somewhat similar configuration to the opening C, and further ornamented around and about the opening E by a series of pointed or spike-shaped protuberances b, similar to the same lettered figures in the sole part or portion of the wear-plate.

I claim—

The design for a wear-plate for boots or shoes, substantially as herein described, and 45 shown in the accompanying drawings.

LOUIS N. BEAUCHEMIN.

In presence of

JOHN C. STOLLEY,
FENLEY BOYLE.
